UNITED STATES PATENT OFFICE.

BÉLA ZSARNAY, OF BELLEVILLE, NEW JERSEY, ASSIGNOR OF ONE-HALF TO ABRAHAM LEWIS, OF NEWARK, NEW JERSEY.

MOUNTED COMBINATION TOY AND CAROUSEL.

1,425,737.

Specification of Letters Patent. Patented Aug. 15, 1922.

Application filed May 26, 1921. Serial No. 472,686.

To all whom it may concern:

Be it known that I, BÉLA ZSARNAY, citizen of Hungary, residing at Belleville, in the county of Essex and State of New Jersey, have invented certain new and useful Improvements in Mounted Combination Toys and Carousels, of which the following is a specification.

This invention relates to mechanical toys, having more particular reference to a toy mounted on wheels and adapted to be propelled along the floor or ground.

The invention has for an object to provide a toy of this type having a novel arrangement of moving devices or figures.

For further comprehension of the invention, and of the objects and advantages thereof, reference will be had to the following description and accompanying drawings, and to the appended claims in which the various novel features of the invention are more particularly set forth.

Fig. 1 of the drawings is a side view of a mechanical toy constructed according to the invention.

Fig. 2 is a partial side view, but showing the parts in a different position from that shown in Fig. 1.

Fig. 3 is a horizontal section on the line 3—3 of Fig. 1.

Fig. 4 is a transverse section on the line 4—4 of Fig. 1.

Fig. 5 is a fragmentary transverse section on the line 5—5 of Fig. 1.

Fig. 6 is a vertical sectional view of the shoulders and head of one of the manikins.

Referring now to the drawings, the reference numeral 10 indicates a longitudinally extending frame element mounted on front wheels 11 and rear wheels 12. The rear wheels 12 serve as drive wheels and are fixed on a shaft 13, the frame being bifurcated at its rear end as at 10' to accommodate certain drive mechanism carried by the shaft 13. The front wheels may be connected to a suitable transverse axle element 14.

Fixed to the front portion of the frame element 10 are diagonal cross bars 16 which support posts 17 whose upper ends have mounted thereon a conical hood 18. Journaled at opposite ends in the hood 18 and frame 10 is a vertical shaft 19 on which is fixed a disk 20 at a distance below the hood 18. This disk 20 has mounted thereon

a series of standards 21 to the upper ends of alternate ones of which are pivotally attached the cars 22 and horses 23, these members 22 and 23 having depending weights 24 rigidly attached thereto whereby they are held in upright position, these weights projecting through suitable slots in the disk 20. To rotate the shaft 19 a pulley 25 is fixed on the lower end thereof and a belt 26 is looped over this pulley 25 and over a pulley 27 on the drive shaft 13. Upon one of the posts 17 is fixed a spring finger 17' adapted to be struck by the weights 24, causing an oscillatory movement to be imparted to the carriages 22 and horses 23.

Behind the carousel structure just described I provide musical devices. As here shown a platform 30 is supported by and above the frame 10 and has fixed thereon a vertically elongated housing 31 in the upper part of which is journaled a shaft 32 adapted to be driven from the drive shaft 13 by means of a belt 33 looped over pulleys 34 and 35 on the shafts 32 and 13 respectively. Upon the shaft 32 is also fixed a toothed wheel 36, the teeth whereof are engaged by a resilient metal strip 37 fixed at its lower end to the platform 30, thereby causing a musical sound to be emitted when shaft 32 is rotated.

Upon the platform 30, in front of the housing 31, a manikin 40 is mounted, this manikin having separate head, body and leg elements joined by steel wires 41 so as to have a vibratory motion upon each other. The arms 40' of the manikin are jointed at the elbows and are pivotally attached to the body as at 42. One of the hands is connected to a crank arm 43 on the shaft 32 and the other has a pivotal connection with the top of the housing 30.

The head 40a of this manikin is preferably of hollow construction (see Fig. 6) having pivoted eyes one of which is indicated at 40b these eyes being mounted on a shaft 40c supported by a bracket 40d. Depending from the shaft 40c is a weighted arm 40e having a forwardly projecting tongue 40f adapted to be projected forwardly and rearwardly between the lips of the manikin as the head vibrates. The wire 41 may be fixed to collars 41' and 41a in the head and body respectively of the manikin.

I also provide other musical elements in the form of concertinas 44 which are fixed

at one end to brackets 45 on the platform 30 and have rigid links 46 connected to their opposite ends, the other ends of these links 46 being connected to the ends of rock levers 47 fulcrumed as at 48 on a bracket 49 on the frame 10. The opposite ends of these rock levers 47 have connected thereto the rods 50 which are connected to the crank disks 51 fixed on opposite ends of a transverse shaft 52 located in front of the shaft 13 and suitably supported by the frame 10. Upon the drive shaft 13 is fixed a gear 53 meshing with a smaller gear 54 on the shaft 52 whereby the latter is rotated.

15 The rock levers 47 are also employed to impart movement to the legs of another manikin 55 disposed at the rear of the device and positioned to have the appearance of propelling the same. This manikin is shown as having the legs 55' jointed at the knees as at 56 and pivotally attached to the body as at 57, while the head 55^a is mounted on the body similarly to the head of the manikin 40. The body of this manikin 55 is fixed to a plate 58 carried by a transverse bar 59 joining a pair of handle extensions 60 projecting rearwardly from the frame 10 and then upwardly and connected by a handle bar 61, adapted to be grasped by the person propelling the toy. The arms 55^b of the manikin 55 are jointed at the elbows and pivotally attached to the body as at 61 and rest upon a cross bar 62 connecting the tops of a pair of posts such as 63 extending upward from the handle extensions 60.

30 To operate the legs of the manikin 55 a pair of links 65 extend rearwardly from the rock levers 47 and are connected at their rear ends to a pair of arms 66 hinged at their upper ends to the handle members 60 and having their lower ends projecting downward behind laterally projecting pins 67 fixed in the ankles of the manikin. The rods 50 which operate the rock levers 47 are connected at diametrically opposed points on the respective crank disks 51, thus causing the levers 47, and in consequence the legs of the manikin, to move oppositely with respect to one another.

45 50 As will be apparent, when the toy is propelled along the floor or ground, or other surface, the disk 20, carrying the horses 23 and cars 22, will be caused to revolve, the manikin 40 will have the appearance of

playing a hand organ, musical sounds being given off by the parts 37 and 41, while the manikin 35 will have the semblance of walking, and propelling the toy.

Having thus described my invention what I claim as new and desire to protect by Letters Patent of the United States is as follows:

1. A toy comprising a frame, wheels on which said frame is mounted, a music box device supported on said frame, a pair of mannikins supported on said frame, one of said mannikins having an arm formed with a hinge-joint at the elbow and pivotally attached to the body of the mannikin, the other mannikin having its legs pivotally attached to its body, and means whereby the free end of the said arm is moved in a circular path in similitude of operating said music box device, and the said legs are oscillated in a similitude of walking.

2. A toy comprising a frame, wheels on which said frame is mounted, a carousel and a music box device supported on said frame, a pair of mannikins supported on said frame, and having their bodies rigid with respect thereto, one of said mannikins having a jointed and pivotally attached arm, the other mannikin having oscillatable legs, a rotary element to which the free end of said arm is connected, said rotary member being arranged to simulate the operating member of said music box device, a pair of oscillatory members adapted to have pushing engagement with the said legs, and means adapted to be operated by said wheels for rotating said carousel and said element and oscillating said members.

3. In a toy, a wheeled vehicle, a manikin having its body supported by the frame thereof and having its legs pivotally attached to the body, and means operated by the vehicle wheels for giving said legs a forward swinging movement, said means comprising a pair of rock levers operatively connected to the vehicle wheels, a pair of arms pivoted adjacent the manikin, links connecting said arms and rock levers, and a pair of pins projecting laterally from the legs of the manikin.

In testimony whereof I have affixed my signature.

BÉLA ZSARNAY.
